UNITED STATES PATENT OFFICE.

HENRY M. BRIGHAM, OF BROOKLYN, NEW YORK.

CARBURETER.

1,114,222.

Specification of Letters Patent.

Patented Oct. 20, 1914.

Application filed January 14, 1913. Serial No. 741,923.

To all whom it may concern:

Be it known that I, HENRY M. BRIGHAM, a citizen of the United States, and residing at Brooklyn, in the county of Kings and State of New York, have invented certain new and useful Improvements in Carbureters, of which the following is a specification, such as will enable those skilled in the art to which it appertains to make and use 10 the same.

This invention relates to carbureters for use in connection with explosive engines using liquid fuel, and the object thereof is to provide a carbureter of this class which 15 will be simple in construction, efficient in operation and economical both in its use and in the manufacture thereof; a further object being to provide a carbureter for the purpose specified which will operate under 20 a substantially constant vacuum throughout its entire range to concentrate upon the fuel spray jet at all times a highly accelerated air supply in order to properly pulverize the liquid fuel and increase its explosive force; 25 a further object being to provide means whereby the effective area of the air intake port or ports will be automatically increased or decreased by the suction of the engine when in operation to correspond with the 30 demands made upon the explosive mixture by the engine, and whereby the fuel intake port or ports will also be increased or diminished in capacity in accordance with the opening and closing of the air intake port 35 or ports, thereby providing means whereby a constant ratio between the quantity of liquid fuel and air supplied to the engine may be maintained at all times and under all conditions, and also to provide simple 40 means whereby the carbureter may be adjusted so as to vary the ratio between the fuel and the air supply, while the engine is running, and with these and other objects in view, the invention consists in a carbureter of the class and for the purpose specified, constructed as hereinafter described and claimed.

The invention is fully disclosed in the following specification of which the accompanying drawing forms a part, in which the separate parts of my invention are designated by suitable reference characters in each of the views, and in which:—

Figure 1 is a central vertical section of my improved carbureter;—Fig. 2 a partial

section on the line 2—2 of Fig. 1;—Fig. 3 a bottom plan view of a base plate and valve seat which I employ in the construction of my carbureter;—Fig. 4 a plan view of a valve which forms a part of my improvement and which, in use, rests on the valve seat shown in Fig. 3, Fig. 5, a bottom plan view of a tripod device which forms a part of the carbureter casing and supports the fuel jet tube;—Fig. 6 a view similar to Fig. 1, but showing only a part of the operative mechanism of the carbureter and showing a modification, and;—Fig. 7 a section on the line 7—7 of Fig. 6.

In the practice of my invention as shown in the drawing, I provide a main casing *a* having a cylindrical bottom portion and a reduced cylindrical top portion *a*² forming a mixing chamber *a*³, and in which is placed a throttle valve *a*⁴ of the usual, or any preferred construction, and the top of the reduced extension *a*² of the casing *a* is provided with a flange or rim *a*⁵ whereby, the carbureter may be secured to the fuel supply connection of an engine cylinder or cylinders in the usual manner.

At one side of the main or bottom part of the casing *a* is a float chamber *b* formed by a casing *b*² secured to, connected, or formed integrally with said casing, and said float chamber is provided with a removable cover *b*³ and float *b*⁴, and the bottom thereof is provided with a supply pipe *b*⁵ and the float *b*⁴ is provided with a valve rod *b*⁶ which passes vertically therethrough and to which said float is secured, and the valve rod *b*⁶ is provided at its lower end with a valve *b*⁷ which controls the flow of the liquid fuel from the pipe *b*⁵ into the float chamber *b*, all these parts of the construction pertaining to the casing *b*² forming the float chamber *b*, the connections thereof, and the float and its operation, being the same as in other devices of this class and forming no part of my invention.

In connection with the bottom of the casing *a* I provide a base plate and valve seat *c* which is circular in form and provided with ears or other projections *c*², and the bottom of the casing *a* is provided with similar ears or projections *a*⁶ and bolts, screws, or similar devices *d* are passed through the ears or projections *a*⁶ and *c*² to secure the base plate and valve seat *c* to the bottom of the casing *a*. I also provide a tripod device

e comprising an annular plate *e*² and downwardly and inwardly curved arms *e*³ which connect with a central head *e*⁴, and the annular plate *e*² of the tripod device *e* is provided with ears or projections *e*⁵ similar to the ears or projections *c*² of the base plate and valve seat *c*, and the bolts, screws or other devices *d* also serve for securing the tripod device *e* to the bottom of the base plate and valve seat *c*, as clearly shown in Fig. 1, and also to the bottom of the casting *a*.

The base plate and valve seat *c* is provided with a spider-work center comprising a central annular hub *c*³ and radial arms *c*⁴ forming large arc-shaped openings *c*⁵, and the hub *c*³ is provided with a depending sleeve *c*⁶ which is exteriorly threaded, as shown in Fig. 1, and on which is screwed a nut *f* provided in its lower side with an annular recess *f*².

The supply pipe *g* which connects the float chamber *b* with the carburetor, communicates, in the usual manner, with the bottom of said float chamber, and screwed into the head *e*⁴ of the tripod device is a vertical liquid fuel jet tube *h* with the lower end of which the tube *g* communicates, as clearly shown in Fig. 1, and the upper end of which extends upwardly through the central hub *c*³ of the base plate and valve seat *c*, and through the sleeve *c*⁶ of said hub, and said jet tube passes through a sleeve *i* mounted in the hub *c*³ of the valve seat *c* and the head *e*⁴ thereof and is vertically movable therein. The lower end of the sleeve *i* is provided with a head *i*² having in the top surface thereof an annular groove *i*³ which corresponds with the groove *f*² in the bottom surface of the nut *f*, and placed between the said nut *f* and the head *i*² of the sleeve *i* is an ordinary expansion spring *i*¹.

The upper end of the sleeve *i* is provided with a yoke-shaped extension *i*⁴ having a top cross head *i*⁵ in which is detachably secured a needle valve *i*⁶ which is designed to regulate the discharge of liquid fuel through the jet tube *h* the upper end of which is provided with a port *h*² through which the needle valve *i*⁶ passes. I also provide a valve *j* which is shown in cross section in Fig. 1 and detached in Fig. 4, and this valve consists of a central hub portion *j*², an annular web portion *j*³ having numerous small ports *j*⁴ and around which is a raised rim portion *j*⁵ provided with a base flange *j*⁶.

The central hub portion *j*² of the valve *j* is threaded interiorly, and the sleeve *i* above the base plate and valve seat *c* is correspondingly threaded exteriorly as shown at *k*, and said valve is screwed on the said sleeve, as clearly shown in Fig. 1, and with this construction the sleeve *i* and valve *j* are vertically removable on the jet tube *h*, as will

be readily understood, and said valve is normally held seated on the base plate and valve seat *c* by the spring *i*¹.

Screwed onto the rim *j*⁵ of the valve *j* is a tapered nozzle tube *m* having an enlarged annular base *m*² by means of which connection is made with the valve *j*, and in the normal position of the parts, as shown in Fig. 1, the nozzle tube *m* projects beyond the needle valve and its support, as clearly shown, and said nozzle tube *m* is movable with the valve *j* and sleeve *i* on the jet tube, as will be readily understood.

In practice I prefer to provide the jet tube *h* with an external surface which is hexagonal in form in cross section, as shown in Fig. 2, in order to reduce friction between the sleeve *i* and said jet tube on which said sleeve is vertically movable and also to provide means to prevent dust, dirt, or other substances from collecting between said sleeve and said jet tube, which result is accomplished or facilitated by the passage of air between said sleeve and tube, in the operation of the carburetor, but my invention is not limited to any particular form in cross section of the jet tube *h*.

It will be understood that the yoke-shaped support *i*⁴ of the needle valve *i*⁶ provides a free discharge of the gasoline or liquid fuel passing through the jet tube *h* into the casting *a*, and it will also be understood that when the parts are assembled, as shown in Fig. 1, the ports or passages *j*⁴ in the valve *j* correspond with, or register with, the large arc-shaped openings, ports or passages *c*⁵ in the base plate and valve seat *c*.

In the normal position of the parts when the apparatus is not in use, the needle valve *i*⁶ is open and air passes in through the valve *j*, and the nozzle tube *m* concentrates this air around the discharge of the jet tube *h*, and causes this air to pass the discharge of the jet tube at a high velocity, and the capacity of the ports *j*⁴ and the nozzle tube *m* is such as to furnish a sufficient mixture of gasoline and air to turn the engine very slowly without any considerable load.

With the engine running and the throttle valve *a*⁴ nearly closed, air is drawn into the carburetor through the valve *j* and base plate and valve seat *c*, and passes through the nozzle tube *m* past the discharge of the jet tube at a high velocity. The liquid fuel, by this operation is drawn out of the jet tube and finely pulverized by the air passing through the nozzle tube and thoroughly mingled with said air, and this composition of air and liquid fuel passes into the cylinder or cylinders of the engine in the usual manner. As the throttle valve is opened and the engine speeds up, the vacuum formed by the above described operation will be increased and the valve *j* will be lifted from its seat, the nozzle tube *m* and

- sleeve *i* being also raised therewith, as shown in dotted lines in Fig. 1, and an additional supply of air will pass into the casing *a* beneath and around the valve *j* and nozzle tube *m* and mingle with the air which is admitted through said nozzle tube, and which will then be overcharged with liquid fuel by reason of the fact that the needle valve *i*³ will be raised with the sleeve *i* so as to enlarge the discharge port *h*² of the jet tube *h*, and in this way the proper ratio between the supply of air and the supply of liquid fuel, as the speed of the engine increased, will be automatically maintained. As the throttle valve *a*⁴ is closed, and the speed of the engine diminishes, the valve *j* will fall, and when the speed of the engine has been sufficiently reduced, said valve will again rest on the seat *c*.
- 10 The needle valve *i*⁶ is tapered so that the relative effective area of the liquid fuel discharge of the jet tube and the air intakes or inlets remain constant throughout the entire range of the carbureter, and the base plate and valve seat *c* is provided with vertical guide pins *n* which pass through suitable recesses or apertures *n*² in the opposite sides of the base flange of the valve *j*, and which prevent the rotation of said valve, and the sleeve *i* may be rotated by means of the head *i*² thereof so as to adjust the needle valve *i*⁶ into any desired position for the purpose of regulating the mixture of air and liquid fuel, and in this operation the valve *j* will remain stationary on the seat *c*, and said operation may be performed while the engine is running, and it will thus be seen that my improved carbureter is provided with both automatic and with hand operated means for maintaining a proper ratio between the amount of air and liquid fuel forming the mixture supplied to the engine. It will also be understood that the needle valve *i*⁶ may be made of any desired taper, but, in practice, I prefer to so taper the said valve that the mixture will contain slightly less than the requisite amount of liquid fuel when no tension is placed on the spring *i*¹¹. As this spring tends to hold the valve *j* on its seat, it will be seen that by tightening the tension of said spring, by means of the nut *f*, the vacuum under which the carbureter operates will be slightly increased as the said valve lifts from its seat, and the percentage of liquid fuel supplied will be increased accordingly. This feature however, is not an essential element in the operation of my carbureter, although, under certain conditions, it is desirable to provide for this additional regulation. The vacuum under which the carbureter operates may, however, be satisfactorily determined by the way of the valve *j*, and the parts attached thereto, and when the needle valve has been properly adjusted as to height, the carbureter will be automatic in its action, and through the suction of the engine and the lifting of the valve *j*, and the needle valve *i*⁶ will accurately maintain the predetermined ratio between the amount of liquid fuel and the amount of air supplied throughout its entire range.
- 15 It has been demonstrated, in practice, that the carbureter so constructed, is very economical in its use of fuel, this result being due to the high velocity of the air current as it passes the liquid spray jet, and the further fact that a very large percentage of the fuel is so finely pulverized that it may be exploded in the engine, and the passage of a similar amount of air between the jet tube *h* and the sleeve *i* which is vertically movable therein and which is made possible by the form of the jet tube in cross section, also facilitates the above described operation, the said air, as it passes between the jet tube and the sleeve, serving to pick up any liquid fuel which may have lodged between said parts, or that may have a tendency to run down between said parts and convey the same back into the nozzle tube *m* where it mingles with the incoming air.
- 20 The construction shown, the needle valve *i*⁶ is provided with a screw threaded shank which passes through the cross head of the yoke-shaped support *i*⁴, and with a set nut *i*⁷ and by means of this construction, the said needle valve may also be adjusted in its support.
- 25 In Fig. 6 of the drawing I have shown a modification of the operative parts of the carbureter, as shown in Fig. 1, in which I substitute for the main air valve *j* a valve *o* having an integral nozzle tube *o*² and a central hub *o*³ provided with a depending skirt sleeve *o*⁴. In this construction, the sleeve *i* incloses the jet tube *h*, as shown in Fig. 1, and said sleeve is threaded, as shown at *i*⁸, and the hub *o*³ of the valve *o* and the depending skirt sleeve *o*⁴ thereof are correspondingly threaded, and said sleeve is provided with vertical slots *i*⁹ four of which are shown in Fig. 7, and the skirt sleeve *o*⁴ of the valve *o* is provided with a plurality of annularly arranged holes *o*⁵ four of which are shown in Fig. 7, and a yoke-shaped spring *p* is passed around the skirt sleeve *o*⁴ and provided with inwardly directed hook ends *p*² which are passed through the holes *o*⁵ and into the corresponding slots *i*⁹ in the sleeve *i*, and the lower end of the sleeve *i* is provided with projecting thumb and finger pieces *i*¹⁰ whereby it may be conveniently turned by hand, and by means of this construction, the needle valve may be adjusted whenever desired by turning the sleeve *i*, but in this operation, with the construction shown, the air valve *o* must be held by taking hold of the skirt sleeve *o*⁴, or said air valve may be held stationary by passing a

suitable instrument up through the base plate *c* and through the air valve, and it will also be seen that with this construction the valve *o* with its nozzle tube *o*² and the sleeve *i* which carries the needle valve, will be operated by the suction of the engine, or be raised by said suction and fall by gravity.

Although I have shown and described the preferred forms of my improved carbureter, or the various parts thereof, and their combination and arrangement, it will be understood that my invention is not limited to the details thereof as herein shown and described and various changes therein and modifications thereof may be made, within the scope of the appended claims, without departing from the spirit of my invention or sacrificing its advantages, and I reserve the right to make all such alterations there in, as clearly come within the scope of the said claims.

Having fully described my invention what I claim as new and desire to secure by Letters Patent is:—

1. In a carbureter of the class described, a casing, a jet tube extending vertically into said casing, means for supplying liquid fuel to said tube, a sleeve vertically movable on said tube and provided at its upper end with a needle valve which extends downwardly into said tube, an air valve mounted on and adjustable on the sleeve and movable therewith, and a nozzle tube carried by the air valve and inclosing the sleeve, the jet tube and the needle valve.

2. In a carbureter of the class described, a casing provided with a base plate having air ports, a movable valve mounted on said base plate and provided with air ports of less dimensions than the ports in said plate and which register therewith, said air valve being provided with a nozzle tube, a jet tube extending vertically into said casing, means for supplying liquid fuel to said jet tube, a sleeve vertically movable on said tube and passing through said air valve, and with which said air valve is connected, and a needle valve supported by said sleeve and operating in the end of the jet tube, the inner ends of the sleeve, and the jet tube and the needle valve being inclosed by the nozzle tube.

3. A carbureter of the class described pro-

vided with a stationary liquid fuel jet tube, a sleeve movable vertically on said tube and supporting a needle valve which operates in the end thereof, a spring for depressing said tube, a base plate through which said sleeve is movable, a valve mounted on said base plate and provided with ports or passages which correspond with other ports or passages in said base plate, said sleeve and said valve having a screw threaded connection, and a nozzle tube connected with said valve and inclosing the inner ends of the sleeve, and the jet tube and the needle valve.

4. In a carbureter, a casing provided with a base plate having annularly arranged ports, a valve mounted on said base plate within said casing and provided with corresponding ports, a nozzle connected with said valve, a sleeve movable vertically through the base plate and extending into the nozzle and connected with said valve and provided at its upper end with a needle valve support, a jet tube support suspended beneath the base plate, a jet tube connected therewith and passing upwardly through said sleeve and on which said sleeve is vertically movable, and means for supplying liquid fuel to said jet tube.

5. In a carbureter, a casing provided with a base plate having air ports, a valve mounted on said base plate and provided with corresponding ports, a nozzle connected with said valve, a sleeve passing vertically through the base plate and through said valve and having a threaded connection therewith and provided at its upper end with a needle valve support, a jet tube support suspended beneath the base plate, a jet tube connected therewith and passing upwardly through said sleeve and on which said sleeve is vertically movable, means for supplying liquid fuel to the jet tube, and a tension device for holding said sleeve in a depressed position.

In testimony that I claim the foregoing as my invention I have signed my name in presence of the subscribing witnesses this 10th day of January, 1913.
